Attorneys.

UNITED STATES PATENT OFFICE

MERTON W. HOWARD, OF LYNN, MASSACHUSETTS, ASSIGNOR TO HOWARD DEVELOPMENT COMPANY, OF LYNN, MASSACHUSETTS, A CORPORATION OF MASSACHUSETTS

NEEDLE LOADER FOR SEWING MACHINES

Application filed February 4, 1930. Serial No. 425,784.

This invention relates to a needle loading device or implement for feeding or inserting needles into the needle bars of sewing machines.

- 5 An object of the invention is to provide a magazine loader of improved construction capable of holding a substantial supply of needles, which is relatively simple in construction and may be readily handled and
 10 manipulated, whereby the needles may be accurately fed from the magazine into the needle bar whenever a new needle is required, such as for the replacement of a broken or damaged needle.
 15 Other objects of this invention will appear in the following description and appended claims, reference being had to the accompanying drawings forming a part of this specification wherein like reference characters designate corresponding parts in the several views.

Fig. 1 is a fragmentary view of a sewing machine illustrating the device of this invention in position with the needle being fed 25 into the end of the needle bar.

Fig. 2 is a side elevation of the needle loader.

Fig. 3 is a top plan view thereof with the cover swung into open position.

30 Fig. 4 is a front end elevation.

Fig. 5 is a sectional view taken substantially on line 5—5 in Fig. 3, looking in the direction of the arrows.

Fig. 6 is a sectional view taken substantially on line 6—6 in Fig. 5, looking in the direction of the arrows.

Fig. 7 is an enlarged detail sectional view showing the stops for positioning and guiding the leading needle in the magazine.

40 Fig. 8 is a detail side view of the construction shown in Fig. 7.

Before explaining in detail the present invention it is to be understood that the invention is not limited in its application to the 45 details of construction and arrangement of parts illustrated in the accompanying drawings, since the invention is capable of other embodiments and of being practiced or carried out in various ways. Also it is to be understood that the phraseology or termi-

nology employed herein is for the purpose of description and not of limitation and it is not intended to limit the invention beyond the terms of the several claims hereto appended as considered in view of the prior art and the requirements thereof. 55

In the drawing I have illustrated a present preferred form of the invention, which is particularly adapted for use in connection with standard types of industrial sewing machines. In the present instance the overhanging arm of the sewing machine is indicated at 20. This arm is provided with guides 21 for receiving the vertically reciprocating needle bar 22. The lower end of the 60 needle bar is provided with the usual hole or socket 23 into which fits the shank N of the needle. The needle is held in position within the socket by means of a thumb screw 24. 65

The needle loader of the present invention comprises a suitable casing 25 slotted in its forward portion to provide a longitudinal raceway or guideway 26 of a size to receive snugly the cylindrical heads or shanks N of the needles. The raceway 26 is of substantial length so as to hold a column of needles, and the base of this raceway is closed by means of a base plate 27 forming a ledge on which the points of the needles rest and are thereby supported. The top of the raceway 75 26 is open to permit the magazine to be filled by the operator. 80

A cover plate 28 is pivoted at 29 to the top of the casing and is adapted to be swung into open position as shown in Fig. 3 to provide 85 access to the raceway, this cover normally being swung into position to close the top of the raceway as shown in Fig. 4. The front end of the cover 28 is formed with a guide sleeve 29a adapted to fit around the needle bar so as to position the loader in the manner shown in Fig. 1 in operative position for feeding a needle into the socket 23 of the needle bar. The guide sleeve 29a is 90 open at its front end to enable it to be fitted around the needle bar, and the base of one side of the sleeve is slotted at 29b. By partially turning the loader on the end of the needle bar the end of the thumb screw 24 will 95 100

be forced into the slot 296 thereby properly positioning the loader.

Operating in the raceway 26 is a follower 30 which is constantly urged forwardly 5 against the column of needles. A link 31 is pivoted at 32 to the follower 30, and this link at its opposite end is pivoted to the upper end of a lever 33. The lower end of the lever is pivoted at 34 to the casing. This lever is 10 acted upon by a spring 35. The spring is bent into U-shape, one end being held in position by means of a stud 36 and the opposite end anchored in a notch 37 at the lower end of the lever 33. It is important to note 15 that the notch 37 is located very close to the pivot 34, and although the spring 35 constantly acts under tension to swing the lever 33 forwardly, the movement of the spring is proportionately very small compared with 20 the movement of the upper end of the lever. This construction results in the application of a substantially constant spring pressure against the follower 30 through the medium of the lever 33 and the link 31 throughout 25 the range of travel of said follower, while at the same time requiring but a minimum movement of the spring 35.

Referring more particularly to Figs. 7 and 8 it will be seen that the raceway or slot 26 30 terminates at its forward end in a pair of stops 38. The working faces 38a of these stops are arcuate in shape so as to conform to the shape of the cylindrical shank of the needle and also to properly guide the needle 35 as it is fed vertically out of the raceway into the needle bar. These stops 38 therefore position the leading needle L in feeding position. Beneath the point of this leading needle the base plate is slotted at 39 to permit 40 vertical reciprocation of the feed slide as hereinafter explained. The guides or stops 38 terminate in shoulders 38b underlying the shoulder at the base of the needle shank (see Fig. 8) so as to support the leading needle in 45 proper position above the slot 39.

Located in a vertical guide slot 40 at the front of the casing is a feed slide 41 capable of reciprocating vertically therein. This slide has a rearwardly projecting toe 42 of 50 a size to move freely through the slot 39 and engage the point of the leading needle. The slide 41 at one side thereof has a projecting lug 43 which projects through a vertical slot 44 in the side of the casing. This lug is anchored in a slot in the end of a lever 45 located on the outer side of the casing. This lever at its rear end is pivoted at 46 to the casing and is provided with a projecting finger piece 47 by means of which it may be 55 pressed upwardly with the operator's finger against the action of a leaf spring 48.

In the operation of the loading device, after it has been positioned in the manner above described and as shown in Fig. 1, the 60 operator presses the operating lever 45 up-

wardly thereby shifting the slide 41 upwardly in the guideway 40. During the upward movement of the slide 41 the toe 42 passes through the slot 39 and engages the point of the leading needle L. As the slide continues upwardly the needle L is carried upwardly into the socket 23 of the needle bar. This movement of the needle is guided accurately by means of the guides 38. When the shank of the needle has been inserted in the socket 23 the clamp screw 24 is tightened, and the loading device is then removed from the end of the needle bar. Thereupon the follower 30, acting against the column of needles, forces another needle into position against the stops 38.

I claim:

1. A needle loading device for a sewing machine having a needle bar, comprising a magazine for holding a column of needles, a spring pressed follower acting against the column of needles, a feed member having means engageable beneath the point of the leading needle of the column for shifting the needle into the needle bar, and means for 85 positioning said device relative to the needle bar.

2. A needle loading device for a sewing machine having a needle bar, comprising a casing having a longitudinal slot to receive a column 95 of needles, a base for supporting needles on their points in said slot, said base having an opening beneath the leading needle of the column, and a vertically movable feed member shiftable through said opening to engage the point of the leading needle and feed the needle vertically into the needle bar.

3. A needle loading device for a sewing machine having a needle bar, comprising a casing having a longitudinal slot to receive a 105 column of needles, a cover shiftable into and out of position on the casing to close or open the upper end of said slot, a base for supporting needles on their points in said slot, said base having an opening beneath the leading 110 needle of the column, and a feed member shiftable through said opening to engage the point of the leading needle and feed the needle vertically into the needle bar.

4. A needle loading device for a sewing machine having a needle bar, comprising a casing having a longitudinal slot to receive a column of needles, a cover shiftable into and out of position on the casing to close or open the upper end of said slot, said cover having means to position the device on the end of the needle bar, a base for supporting needles on their points in said slot, said base having an opening beneath the leading needle of the column, and a vertically movable feed member shiftable through said opening to engage the point of the leading needle and feed the needle vertically into the needle bar.

5. A needle loading device for a sewing machine having a needle bar, comprising a 130

casing having a longitudinal slot to receive a column of needles, a base for supporting needles on their points in said slot, said base having an opening beneath the leading needle 5 of the column, a vertically movable feed member shiftable through said opening to engage the point of the leading needle and feed the needle vertically into the needle bar, and means for positioning said casing on the end 10 of the needle bar.

6. A needle loading device for a sewing machine having a needle bar, comprising a casing having a longitudinal slot to receive a column of needles, a follower in said slot 15 acting against the column of needles, a lever pivoted at one end to the casing and connected at its opposite end to said follower, and a spring acting against the lever adjacent said pivot.

20 7. A needle loading device for a sewing machine having a needle bar, comprising a casing having a longitudinal raceway to receive a column of needles, a follower slidable in said raceway against the rear of the column, 25 a lever having a connection at one end to the follower and pivoted to the casing at its opposite end, a spring acting on said lever adjacent said pivot and remote from said connection, and means for successively feeding 30 needles from the forward end of the column into the needle bar.

8. A needle loading device for a sewing machine having a needle bar, comprising a casing having a longitudinal raceway to receive a column of needles, a follower slidable in said raceway against the rear of the column, a lever having a connection at one end to the follower and pivoted to the casing at its opposite end, a spring acting on said lever 40 adjacent said pivot and remote from said connection, and a reciprocating feed member operable vertically against the point of the leading needle of the column for feeding it vertically into the needle bar.

45 9. A needle loading device for a sewing machine having a needle bar, comprising a casing having a longitudinal raceway to receive a column of needles, a follower slidable in said raceway against the rear of the column, a lever having a connection at one end to the follower and pivoted to the casing at its opposite end, a spring acting on said lever adjacent said pivot and remote from said connection, said casing having a vertical 50 guideway in front of the column, a feed slide in said guideway having a projection underlying the point of the leading needle of the column, and an operating member for shifting said slide to cause the projection to feed a 55 needle out of said guideway.

60 10. A needle loading device for a sewing machine having a needle bar, comprising a casing having a longitudinal raceway to receive a column of needles, a follower slidable 65 in said raceway against the rear of the col-

umn, a lever having a connection at one end to the follower and pivoted to the casing at its opposite end, a spring acting on said lever adjacent said pivot and remote from said connection, said casing having a slideway in 70 front of the column, a feed slide in said slideway having a projection normally underlying the point of the leading needle of the column, and a manually operable lever pivoted to the casing for operating said slide 75 thereby causing said projection to feed a needle out of the guideway.

In testimony whereof I affix my signature.
MERTON W. HOWARD.
